T. VARNEY.
QUARTZ MILL.

No. 63,675.

Patented Apr. 9, 1867.

United States Patent Office.

THOMAS VARNEY, OF SAN FRANCISCO, CALIFORNIA.

Letters Patent No. 63,675, dated April 9, 1867.

IMPROVEMENT IN QUARTZ-MILLS.

The Schedule referred to in these Letters Patent and making part of the same.

TO ALL WHOM IT MAY CONCERN:

Be it known that I, THOMAS VARNEY, of the city and county of San Francisco, and State of California, have invented certain new and useful improvements in Quartz-Grinders used in pulverizing gold and silver ores, and for other similar purposes; and I do hereby declare that the following is a full, clear, and exact description of the same, reference being had to the annexed drawings, making a part of this description, in which—

Figure 1 is substantially a vertical central section view of a quartz-grinding machine having my improvements.

Figure 2 is a perspective view of the lower grinder; and

Figure 3 is a view from beneath of the lower or grinding face of the upper grinder.

Similar letters of reference indicate corresponding parts in the different figures. (By mistake a different style of letter has been used in the drawings from that in the specification.)

The nature of my invention consists in the use of two grinders with comparatively large diameter and small height, one stationary and the other revolved horizontally, their grinding faces being smooth and even, except so far as rendered otherwise by slots sunk into them up and down, and filled with wood or some equivalent substance, and so formed (the faces) that the space between them shall have and retain a certain form, to wit, one that commences above with a thickness sufficient to admit the ore to be ground, and thence descends, at first, vertically, then gradually curving downward and outward, at the same time gradually diminishing in thickness until at the lower and outer part it becomes nearly or quite horizontal, and the faces come nearly or quite in contact with each other.

The body of the machine consists of the shell *a*, fig. 1, resting upon the legs *b*, and bolted thereto through lugs on its periphery. Through the bottom of this shell at one side is the discharge opening *c*. The vertical shaft *d* is stepped into the box *e* in the ordinary manner, and is adjusted vertically by means of the lighter bar *f* and hand-wheel *g*. To the shaft *d* is keyed the driver, being a hub, *h*, with two arms *i*. In the upper end of this hub is a hemispherical socket in which rests the correspondingly formed projection *j* of the centre piece *k*. To this centre piece is fastened by the bolts *l* the revolving grinder *m*, on the under side of which are the lugs *n*, (shown by the dotted lines,) against which the arms of the driver press. Upon the top of the grinder *m* is placed the cap *o*. The stationary grinder *p* is fastened to the shell *a* by the bolts *r*. The upper end of the shaft *d* runs in the box *s* in the arched cross-piece *t*, which is bolted to the stationary grinder *p*. This grinder extends sufficiently above the other to allow for wear, and to form a receptacle for the material to be ground. The shaft is driven by the gearing shown, or any of the ordinary methods. The grinders are of hard cast iron or some other hard material. The form of the grinding surfaces is such that their lines in a vertical central section view, as in fig. 1, are quarter circles, tractory curves, or curves substantially like them, so modified, however, as to produce the kind of opening between the grinding surfaces above indicated, to wit, one commencing at the top of a size sufficient to admit the material to be ground, and thence gradually diminishing as it extends downward and outward until at the periphery the grinding faces come in contact with each other, or nearly so. The advantage of this kind of opening is that it receives the material to be ground coarse, and gradually reduces it and discharges it as fine as desired by a single passage between the grinders without the expenditure of the time and power involved in the ordinary pan method. But it is absolutely necessary that this opening should retain its form as above described, and as the method of securing this constitutes one of the claims I make, I will describe it particularly.

All grinding machines heretofore used having grinding faces of the same general form as mine have been constructed on substantially the tractory conoidal principle, that is to say, the grinding surfaces have had the form described by the revolution of the tractory curve about the line of traction. The chief characteristic of such surfaces is that when fed at all parts with like material, and while the space between the grinding surfaces is of the same thickness throughout, the faces retain their original form; but if the opening be enlarged above so as to allow the feed to enter coarse and become finer as it descends, the comparative wear above is less than below, so that the wedge-shaped opening between the grinders gradually disappears till the faces of the grinders come in contact with each other throughout their entire faces, and the feed and work done grow less and less, and at last almost entirely cease. To prevent this result it is necessary to cause an increased wear above. This I accomplish by expanding, as it were, the old form horizontally, that is to say, while the curve

of the faces up and down remains the same, the diameters of the grinders are increased. This increases the velocity of the upper more than it does the lower parts, and consequently increases the wear above more than that below. In other words, with grinding faces having their vertical sections of the form above described, and a fixed or constant height, if we bring their upper parts to a point at the centre of motion, these upper parts, having no motion, will not grind at all, while the parts below will have a velocity and grinding capacity in proportion to their distances from the centre of motion. This is one extreme. Now if we expand the grinding surfaces horizontally infinitely, (leaving their height and vertical form the same,) the upper will have the same velocity as their lower parts. This is the other extreme. Between these extremes we select the mean suited to our purpose. Starting from the first-named extreme, by expanding the grinders horizontally until their base is four times their height, the wear will be substantially like that of grinders constructed on the tractory principle, in which the grinding surfaces when equidistant from each other at all points, and when fed at all points with like material, wear in proportion at all points and preserve their original form. But with this relative diameter and height, if we should make the wedging opening between the grinders and feed with coarse material, the result would be that the lower parts would wear faster than the upper ones, and the opening would soon disappear. To obviate this we have only to continue the expansion until the velocity above compared with that below is sufficient to cause wear above to such a degree compared with that below as to preserve the opening required. It will be apparent that the larger the opening is at the top, the greater the diameter should be compared with the height in order to preserve that opening. For grinding fine material like ordinary sand, (when the opening required above is slight,) the opening will be preserved by having the diameter but slightly in excess of four times the height; but for grinding material of the size of wheat, the diameter should be at least five times the height, and for every increase in the size of the material there should be a corresponding increase of diameter. The grinders are made with increasing thickness from the upper edge to the periphery, thus making the thickness of each part in proportion to its wear, so that when worn out nothing remains to throw away but a thin shell of uniform thickness. If desired, each grinder may be composed of a shell with shoes fastened thereto, the shoes occupying the spaces between the wooden slots. This arrangement allows the shell to be used permanently, and the shoes to be removed and renewed at pleasure. This is the proper style for large mills. Up and down the faces of the grinders, at short distances from each other, are sunk into the grinders, and nearly through them, slots or channels which are filled with hard wood *w* driven in endwise and cut off flush with the face, leaving the face when new perfectly smooth and even. These channels for the wood may be at right angles to the line of motion or varied therefrom. By making them so that while in motion the upper ends shall be in advance of the lower, the discharge will be facilitated. It is not indispensable that the wood should in all cases extend to the top of the grinding faces. From the top, part way down, corrugations may be substituted, but the lower parts of the faces should be made as described.

The operation is as follows: On setting the shaft in motion the arms of the driver press against the lugs *n*, on the lower side of the lower grinder and revolve it. The joint between the projection *j* and hub *h* allows the faces of the grinders to adjust themselves to each other. Instead of this joint the lower grinder may be attached rigidly to the shaft, if desired. The speed should be considerable, sufficient to cause a proper discharge. With a slow movement and the faces of the grinders set for fine work, the ore will pass through very slowly. Centrifugal force must be mainly depended upon for a proper discharge. The ore may be introduced by any of the ordinary methods for hopper feeding, and should be accompanied by a constant stream of water of a size sufficient, at least, to produce an amalgamating pulp. Immediately on entering between the grinders the ore becomes distributed, the coarse remaining above and the fine going further down according to its fineness. The wood being softer, keeps worn slightly in advance of the iron, leaving a shallow groove along the face of the wood, down which ore passes of larger size than could otherwise penetrate the same distance downward. The ore in these grooves is held up by the wood of the lower, and down by the wood of the upper grinder, so as to be caught by the opposite iron surface and further reduced, the grooves serving as feeders to the iron surfaces. The greatest wear takes place on one side of the wood, from whence it (the wear) diminishes gradually to the opposite side, where the wood remains flush with the iron face. The side least worn is the one first reached by the ore in its horizontal movement. Another peculiarity of this worn groove is that it is comparatively deep at the upper end, and gradually diminishes in depth as it descends, until near and at the periphery it totally disappears, or very nearly so, leaving the grinding faces there smooth and even, thus effectually preventing the escape of the ore until it is reduced to the fineness desired. The rule seems to be that the size of the groove on any given line about the faces of the grinders will be in proportion to the size of the ore on that line, which itself depends upon the distance of the grinders from each other on said line.

From the foregoing it will be apparent that the form of the opening between the grinders, as well as that of the grooves along the wood, is self-preserving; that the faces of the grinders are, as it were, kept constantly dressed by their own operation.

Having thus described my invention, what I claim as new, and desire to secure by Letters Patent, is—

The combination of the slots in the smooth grinding surfaces filled with wood, with the peculiar form of the revolving grinder *m*, and stationary grinder *p*, when constructed and operating substantially as described, and for the purpose as set forth:

THOMAS VARNEY.
